TOBACCO MANIPULATING MACHINE

Walter Everett Molins, Deptford, London, England; Harold Bernardo Molins and Moses Hyman Isaacs, executors of said Walter Everett Molins, deceased, assignors to Molins Machine Company Limited, London, England

Application March 22, 1935, Serial No. 12,498
In Great Britain March 23, 1934

5 Claims. (Cl. 131—43)

This invention is for improvements in or relating to tobacco manipulating machines in which a continuous filler rod is formed, such for example, as continuous rod cigarette making machines in which a continuous tobacco filler rod is severed to form it into lengths, or in tobacco packaging machines in which a continuous tobacco filler rod is formed, but in which such filler rod is of a larger cross section than in the case of a filler of a continuous rod cigarette making machine, and this larger filler rod is severed into sections or lengths for subsequently inserting into packages.

Where throughout the specification and claims the term "mass" is used, it shall mean weight per unit length considered in the direction of movement, and the term "desired mass" shall be taken to mean the weight, or substantially the weight per unit length which it is desired that the continuous tobacco filler rod shall have.

The term "axial" when used hereinafter shall be deemed to include "lengthwise", and when used in connection with direction refers to the general direction of movement of the tobacco filler rod or the tobacco stream or the tobacco fed to the filler rod.

The expression "continuous tobacco filler rod" when used herein and in the appended claims means a rodlike stream of tobacco of a cross-section comparable with that included within a wrapper (for example, the paper wrapper of a cigarette) which is finally to contain the filler rod, which rodlike stream is continuously moved axially of itself, and the expression is not to be taken as limited to a filler rod of any given length or width or even to the final filler rod which is severed into sections, since the filler rod after being formed in accordance with the present invention may be subjected to further treatment, which further treatment forms no part of the present invention, nor is the expression to be taken to include a tobacco carpet which is formed in a hopper, and then fed (e. g., picked and showered) therefrom preparatory to commencing the formation of the filler rod.

According to one form of the present invention there is provided a method of forming a continuous tobacco filler rod by feeding tobacco axially to a point or successive points at which, or at each of which, its velocity is reduced and controlling it within predetermined limits considered transversely of its direction of movement at or in the region of that point or of each point.

According to another form of the present invention there is provided a method of forming a

continuous tobacco filler rod and of selecting and controlling the mass thereof by feeding tobacco to a position at which its velocity is reduced whilst simultaneously confining said tobacco transversely of its direction of movement within a passage which has a substantially constant cross-section and which embraces the region of reduction of velocity in such manner that compacting of the tobacco is brought about by axial compression produced by said reduction of velocity in said passage.

According to another form of the present invention there is provided in or for a continuous rod tobacco manipulating machine, apparatus for forming a continuous tobacco filler rod according to either of the methods set out above, said apparatus comprising in combination a conveyor device for moving tobacco forwardly, conveyor means to feed tobacco in the same general direction towards the conveyor device and at a higher velocity than the conveyor device moves the tobacco forwardly, and control means to control the tobacco within predetermined limits considered transversely of its direction of movement at or in the region of the point at which the velocity of the tobacco changes. The said control means may comprise a passage of substantially constant cross-section. The conveyor device may co-operate with the control means to form therewith a part of a control passage and the conveyor means may comprise an endless conveyor which co-operates with the control means to form therewith a part of a control passage. The velocities of the conveyor device and the conveyor means may be adjustable relatively one to the other, and a part at least of the control means (e. g., the top and side walls of the control passage) may be stationary.

The apparatus for forming a continuous tobacco filler rod may be used in combination with a tobacco feeding mechanism, which latter feeds tobacco on to the said conveyor means at a sufficient rate in relation to the velocity of the slower moving conveyor device to provide a filler of the desired mass, and the said conveyor means moves the tobacco forwardly at a sufficiently high velocity that the tobacco conveyed by it (for example, in the form of a stream) is, at substantially all points considered in the direction of movement of the tobacco, below the desired mass.

One or more intermediate conveyors may be provided between the said conveyor device and the said conveyor means respectively to provide successive reductions in the velocity of the tobacco and control means may be provided at

each point where there is a reduction in velocity.

The present invention also provides a continuous filler rod made according to the present invention and a cigarette made from the said filler rod.

One construction made in accordance with the present invention will now be described by way of example, with reference to the accompanying drawings, in which:

10 Figure 1 is a sectional side elevation of apparatus for forming a continuous tobacco filler rod.

Figure 2 is a section taken along the line A—A of Figure 1 looking in the direction indicated.

15 Figure 3 is a section taken along the line B—B of Figure 1, looking in the direction indicated.

Figure 4 is an enlarged view of a portion of Figure 1.

Figure 5 is a diagrammatic side elevation of a part of a cigarette making machine, and shows 20 a complete arrangement of the driving mechanism for the parts concerned with the invention.

Figure 6 shows a part of Figure 5 to an enlarged scale.

Figure 7 is a plan of some parts of Figure 6.

25 Figure 8 is an end view showing the driving mechanism for driving the band 1.

Figure 9 is a view on the line 9—9 of Figure 8.

Figure 10 shows the driving mechanism for driving the slower moving band 8.

30 Like reference numerals refer to like parts throughout the specification and drawings.

Referring to Figure 1, tobacco is showered or otherwise fed, for example, as a sliver, from a tobacco feeding apparatus 16, which may be of 35 any suitable form, and the tobacco is delivered on to conveyor means shown in the example as an endless moving conveyor band 1, which travels on the bottom of a trough 7. The tobacco showered or otherwise fed on to the conveyor band 1 is guided laterally between the walls of 40 the trough 7. As the tobacco is carried along by the conveyor 1, rollers 8 and 9 engage the tobacco and are rotated in a direction such that that part of the surface of each roller which 45 engages the tobacco moves with the tobacco.

45 In Figure 1 the tobacco has been shown falling vertically, but if desired the tobacco before reaching the conveyor 1 may have a component of movement in the direction of movement of the conveyor 1.

50 The tobacco is fed axially by the conveyor 1 over a bridge piece 2, and is received thereafter on a conveyor device 3, which in the example shown, is constituted by a continuous web of paper. An endless conveyor tape 5 is provided to support the paper web 3, and the tape 5 and web 3 are moved forwardly at the same speed.

55 The direction in which the parts are moved is shown by arrows in Figure 1. The paper web 3 is fed over a guide roller 4. The bridge piece 2 is located between the guide roller 4 and a roller 15 about which the band 1 rotates and spans the gap between the conveyors 1 and 3.

A controlling member 6 is provided above the 60 conveyors 1 and 3. The member 6 may be made in two portions as shown and it is provided with an upward extension 66 having apertures 61. The member 6 is secured to a frame 62 by means of screws 63 with a distance piece 64 provided 65 between the extension 66 and the frame 62. The apertures 61 are made larger than the diameter of the screws 63 so that the member 6 can be 70 adjusted lengthwise of the conveyors 1 and 3 and vertically. The frame 62 is pivoted at 75 65, which pivot is supported on the main bed

of the machine. Side guides 10 are also arranged, as shown, and are supported by means of distance pieces 12 secured to plates 13 fixed to the trough 7. Curved guides 11 are also provided to prevent the tobacco from spreading laterally on the conveyor 3. The guides 11 are fixed to the bed of the machine by securing them to the distance pieces 12, the thickness of which pieces 12 have been reduced at this point as shown in Figure 3.

10 The guides 10 terminate at a point substantially below the axis of a compression roller 14 and the guides 11 are made sufficiently long to keep the tobacco under control until it moves into another controlled space, such as between 15 the walls of a garniture, not shown, and under the usual compression tongue 17. The compression roller 14 is carried on a frame 66. The distance of the roller above the conveyor 3 can be regulated owing to the fact that the frame 20 66 is pivotally mounted about the pivot 65 and is clamped to the frame 62 through a slot 67 in the frame 66. The roller 9 is supported on a spindle 90 carried on the frame 62. The whole frame 62 is capable of being swung about the 25 pivot 65 to allow access to the various parts.

A stop 91 is provided to support the free end of the frame 62. This support may be adjustable to regulate the height of the axis of the 30 spindle 90.

35 It will be seen that the conveyors 1 and 3, the bridge piece 2, the side guides 10 and 11, the member 6 and the rollers 8 and 14 constitute the various walls of a control passage, the purpose of which will be described later.

In order to prevent jamming or choking of the tobacco in the control passage, the side walls 10 are non-convergent and the passage may be arranged so that its cross-sectional area increases very slightly from the inlet to the outlet, and it has been found that jamming will not necessarily occur if the top wall 6 of the said passage is sloped slightly downwards towards the exit. For instance a divergence of 0.01 or 0.02 of an 40 inch of the walls 10 has been found sufficient for this purpose. This may be done whether or not the top member 6 has a downward slope towards the conveyor 3, and this slope may make any suitable angle with the conveyor 3 provided that the downward slope is not too steep so as to render jamming or choking likely. It is found, however, that better results are obtained if the height of the passage is the same along its effective length, that is to say, the length in which packing occurs. It will be understood that in 45 all cases the passage is substantially constant along its effective length, that is, a passage having a substantially constant cross-section, and it will be further understood that the expression "passage of substantially constant cross-section" when used in the claims refers only to the effective length of the passage, since beyond the effective length, e. g., at the entrance to and the exit from the passage, the cross-section may, if desired, no longer be substantially constant.

50 If desired, a rail (not shown) may be provided above the conveyor 1 instead of the rollers 8 and 9 to engage the top of the tobacco carried thereby. The rollers 8 and 9, however, have the advantage in that the surfaces which engage 55 with the tobacco move with the latter, thereby avoiding unnecessary friction between the tobacco and the conveyor 1.

The operation of the apparatus is as follows: 60 The whole of the mechanism is driven from 75

the main shaft 100 which is rotated by any suitable means, such, for example, as an electric motor. The fast moving band 1 is driven by a gear wheel 101 which meshes with a pinion 102 secured to a stub shaft 103. A spiral gear 104 is secured to the stub shaft 103 and meshes with a gear wheel 105 secured to the shaft 106. The driving pulley for the band 1 is, as can be seen, also secured to the shaft 106.

10 The slower moving conveyor 5 also receives motion from the main shaft 100. In this case there is a gear wheel 107 secured to the shaft 100 and meshing with a gear wheel 108 secured to the shaft 109 on which is also mounted the 15 pulley which drives the slower moving conveyor 5.

The wheels 8, 9 and 14 are also rotated from the main drive shaft 100, a worm gear 110 being secured to the shaft 100 and cooperating with 20 a gear wheel 111 secured to a spindle 112 which is, as can be seen from Figure 6, substantially at right-angles to the main drive shaft 100. The spindle 112 has secured to it a worm gear 113, and cooperating with the worm 113 are two gears 25 114 and 115. The gear 114 is secured to a spindle 116 to which is also secured the wheel 14. Gear wheel 115 is secured to a spindle 117, and has an extended sleeve 118 on the end of which is formed a gear wheel 119 which cooperates with 30 a gear wheel 120 secured to the shaft 90 to which the wheel 9 is secured. The wheel 8 is driven by means of a belt 121 which connects a pulley 122 secured to the shaft 116 with a pulley 123 secured to the spindle 124 to which the wheel 35 8 is secured.

The speed of the conveyor 1 can be varied by changing the motor speed, while the speed of the conveyor 3 may be controlled by means of a change speed device of any suitable construction.

40 The driving mechanism described above is conventional, and its details form no part of the present invention.

The conveyor 1 is moved at a greater velocity than the conveyor 3, which latter moves at the normal velocity in relation to the rate at which the tobacco feeding apparatus feeds tobacco, that is to say, the speed at which the conveyor 3 moves is such that the quantity of tobacco fed by the tobacco feeding apparatus 16 is sufficient 45 to provide a filler rod of the required mass.

In the illustration shown in Figure 1, the tobacco on the conveyor 1 is shown in the form of a stream which at substantially all points along its length is below the desired mass. The velocity at which the conveyor 1 travels relatively to the conveyor 3 and to the rate of working of the tobacco feed governs the mass of the tobacco on the conveyor 1 and it will be seen that the faster the conveyor 1 moves the less will be the mass of tobacco on the conveyor 1. For instance, if the conveyor 1 is moved at a sufficiently high speed, it will be seen that the mass of tobacco received upon the conveyor 1 can be made very small. It will be appreciated that the velocity of the conveyors 1 and 3 respectively may be adjustable to any desired extent.

The tobacco shown on the conveyor 1 in Figure 1 is fed as a stream towards the control passage. 70 Within the control passage there is always a point at which the reduction in velocity of the tobacco occurs, and it can be seen that at this point the tobacco impacts against the slower moving tobacco and forms it into a filler rod. The tobacco whilst in the control passage is thus packed

by axial compression produced by the reduction of velocity in the passage, and the walls of the passage control the tobacco by keeping it within predetermined limits considered transversely of its direction of movement at or in the region of 5 the point at which the reduction in velocity occurs.

The filler rod is thus formed or built up and is removed from the control passage by the conveyor 10 3 which latter is assisted by the roller 14.

It will be obvious that the point at which the merging or impact occurs will remain constant if all the conditions of the apparatus and the consistency of the fast moving tobacco remain constant. If, however, the mass of tobacco fed is 15 irregular, the impact point will move in an axial direction; for example, if the mass of tobacco brought by the fast moving conveyor 1 be reduced, the point at which the impact occurs will advance in the direction of movement of the slower moving conveyor. Conversely, if the mass of tobacco brought by the fast moving conveyor increases, the impact point will recede, that is, move in a direction opposite that in which the slower moving conveyor is travelling, so that the packing will 20 occur earlier. Due to this shifting of the impact point, irregularities in the tobacco fed are less in the finished filler rod when made according to the present invention than in a filler rod when made by the usual known methods, so that the present 25 invention enables a more uniform filler rod to be formed.

It will be seen that since the packing point varies in an axial direction, the control passage 30 must be sufficiently long to enable the tobacco to be compacted wherever the packing point may be at any given moment.

It will be seen, therefore, that compacting is effected in a passage which is of substantially 35 constant cross section along its effective length, 40 and that a continuous tobacco filler rod can be formed for a cigarette rod on a cigarette making machine having at least a speed whereby over 32 ounces avoirdupois of continuous tobacco filler rod is formed per minute. In the case of a cigarette making machine, such a filler rod of over 32 ounces per minute is formed when the machine is producing 25 cigarettes per ounce at the rate of over 800 cigarettes per minute.

Instead of making the top surfaces of the conveyors 1 and 3 in alignment, as shown, they may be inclined relatively to one another. For example, the conveyor 1 may be higher at the right hand side, looking at Figure 1, than at the point of junction between the conveyors 1 and 3. Although in such a case the direction of movement of the tobacco has changed, it will be appreciated that the general direction of movement of the tobacco forming the filler rod has not been changed, and it will be understood that when describing the movement of the tobacco along the two conveyors in such a case, the term "axial" is deemed to include the general direction of movement of the tobacco along the conveyors.

Instead of using the construction shown in Figure 1 whereby the filler rod is formed in one stage, the filler rod may be formed in stages. In such a case the tobacco will be built up as shown in Figure 1, but there will be a further stage or 70 stages at each of which the mass of the tobacco moving forwardly will be increased, until finally the tobacco is fed to the rear end of the filler rod. In such a case, one or more intermediate conveyor devices may be provided between the conveyor 1 75

and the conveyor 3, and such conveyors will have speeds which are between the speeds of the conveyor 1 and the conveyor 3 respectively, but which gradually decrease from the conveyor 1 to the conveyor 3. Control means are provided at the junction between each of the adjacent conveyors to form control passages, such as described with reference to the illustration in Figure 1, so that there is a controlled packing at each stage.

10 It will be appreciated that in the case where intermediate conveyors are provided, these may also be adjustable in their speeds, as is the case with the conveyors 1 and 3.

What is claimed is:

15 1. In apparatus for forming a continuous tobacco filler rod, a first conveyor having a relatively smooth surface for feeding tobacco particles in a stream, a second conveyor having a relatively smooth surface to continue the feeding of the stream at a linear speed less than that at which it is fed by the first conveyor, the relative speeds of said conveyors being such that the greater velocity of the tobacco particles on said first conveyor will cause the same to compact on 20 slower moving particles, and a passage through which the stream is fed, having a generally uniform transverse sectional area and in which a continuous tobacco filler rod is formed by the axial compacting of the tobacco in the passage to 25 a substantially constant cross-section which is determined by the confining walls of the passage, said passage being of sufficient length to extend on either side of the point of compacting of the stream as measured axially.

30 2. In apparatus for forming a continuous tobacco filler rod, a first conveyor having a relatively smooth surface for feeding tobacco particles in a stream, a second conveyor having a relatively smooth surface to continue the feeding of the stream at a linear speed less than that at which it is fed by the first conveyor, the relative speeds of said conveyors being such that the greater velocity of the tobacco particles on the 35 said first conveyor will cause the same to compact on slower moving particles, and a passage through which the stream is fed and in which a continuous tobacco filler rod is formed by the axial compacting of the tobacco in the passage to a substantially constant cross-section which is determined by the confining walls of the passage, said passage being of sufficient length to extend on either side of the point of compacting of the stream as measured axially and having a generally uniform transverse sectional area, said conveyors each forming a part of said passage.

40 3. In apparatus for forming a continuous tobacco filler rod, a first conveyor having a relatively smooth surface for feeding tobacco particles in a stream which is at substantially all points below the mass which it is desired that the continuous tobacco filler rod shall have, a second conveyor moving at a linear speed less than that of the first conveyor and having a relatively

smooth surface, said second conveyor being arranged to continue the movement of the tobacco as a stream, the relative speeds of the said conveyors being such that the greater velocity of the tobacco particles on said first conveyor will cause the faster moving tobacco particles to compact on the slower moving particles and increase the mass of the tobacco to the desired mass and a passage through which the stream is fed and in which a continuous tobacco filler rod is formed by the axial compacting of the tobacco in the passage to a substantially constant cross-section which is determined by the confining walls of the passage, said passage being of sufficient length to extend on either side of the point of compacting of the stream as measured axially and having a generally uniform transverse sectional area. 10

4. In apparatus for forming a continuous tobacco filler rod, a first conveyor for feeding tobacco in a stream which is at substantially all 20 points of less than the desired mass, a second conveyor to receive the tobacco stream fed by the first conveyor and to continue the feeding of the stream at a less linear speed than that at which it is fed by the first conveyor and a passage through which the stream is fed and in which a continuous tobacco filler rod is formed by the axial compacting of the tobacco in the passage to a substantially constant cross-section which is determined by the confining walls of the 25 passage, said passage being of sufficient length to extend on either side of the point of compacting of the stream as measured axially whereby the stream is compacted to increase the mass thereof to the desired mass. 35

5. In apparatus for forming a continuous tobacco filler rod, a first conveyor having a relatively smooth surface for feeding tobacco particles in a stream which is at substantially all points below the mass which it is desired that the continuous tobacco filler rod shall have, a second conveyor moving at a linear speed less than that of the first conveyor and having a relatively smooth surface, said second conveyor being arranged to continue the movement of the tobacco as a stream, the relative speeds of the said conveyors being such that the greater velocity of the tobacco particles on said first conveyor will cause the faster moving tobacco particles to compact on the slower moving particles and increase the mass of the tobacco to the desired mass and a passage through which the stream is fed and in which a continuous tobacco filler rod is formed by the axial compacting of the tobacco in the passage to a substantially constant cross-section which is determined by the confining walls of the passage, said passage being of sufficient length to extend on either side of the point of compacting of the stream as measured axially and having a generally uniform transverse sectional area, said conveyors each forming a part of said passage. 50

WALTER EVERETT MOLINS.
